Primary Examiner — Ruth McInroy(74) *Attorney, Agent, or Firm* — McAndrews Held & Malloy, Ltd.(57) **CLAIM**

The ornamental design for a dust canister for cleaner, as shown and described.

DESCRIPTION

FIG. 1 is a front perspective view of a dust canister for cleaner showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along the line 8-8 of FIG. 6; and,

FIG. 9 is an exploded front perspective view.

The dashed broken lines in the drawings represent portions of the dust canister that form no part of the claimed design.

1 Claim, 8 Drawing Sheets(56)
